(57) **CLAIM**

The ornamental design for a conduit fitting ring, as shown and described.

DESCRIPTION

FIG. 1 is a top and side perspective view of a conduit fitting ring, showing our new design;

FIG. 2 is a bottom and side perspective view thereof;

FIG. 3 is a top plan view thereof;

FIG. 4 is a bottom plan view thereof;

FIG. 5 is a side elevation view thereof, as seen from line 5—5 in FIG. 3;

FIG. 6 is another side view thereof, as seen from line 6—6 in FIG. 3; and,

FIG. 7 is a bottom perspective view thereof, in use condition. The broken line shown in FIG. 7 is included for the purpose of illustrating environment and forms no part of the claimed design.

UNITED STATES PATENT AND TRADEMARK OFFICE
CERTIFICATE OF CORRECTION

PATENT NO. : D635,934 S
APPLICATION NO. : 29/377346
DATED : April 12, 2011
INVENTOR(S) : Xing-Guo Shen et al.

Page 1 of 1

It is certified that error appears in the above-identified patent and that said Letters Patent is hereby corrected as shown below:

On the title page, the statement in the description reading

“The broken line shown in Fig. 7 is included for the purpose of illustrating environment and forms no part of the claimed design”

should be changed to

-- Throughout the figures, the dashed broken lines show unclaimed structure or environment, and form no part of the claimed design. The dash-dot broken lines represent the boundary between claimed and unclaimed areas and form no part of the claimed design. --
